(57) **CLAIM**

The ornamental design for a corkscrew handle, as shown and described.

DESCRIPTION

FIG. 1 is a perspective view of our new design for a corkscrew handle;

FIG. 2 is a top plan view thereof;

FIG. 3 is a bottom plan view thereof;

FIG. 4 is a left side elevation view thereof;

FIG. 5 is a front elevation view thereof, the rear elevation view being a mirror image thereof; and,

FIG. 6 is a right side elevation view thereof.

The broken line showing is for illustrative purposes only and forms no part of the claimed design.
